UNITED STATES PATENT OFFICE.

JOHN A. DAVIS, OF THE UNITED STATES NAVY, ASSIGNOR OF ONE-HALF TO FRED S. LINCOLN, OF WASHINGTON, DISTRICT OF COLUMBIA.

TALKING-MACHINE.

1,360,900.

Specification of Letters Patent. Patented Nov. 30, 1920.

Application filed March 22, 1920. Serial No. 367,824.

To all whom it may concern:

Be it known that I, JOHN A. DAVIS, of the United States Navy, a citizen of the United States of America, and whose post office address is c/o Navy Department, Washington, D. C., have invented certain new and useful Improvements in Talking-Machines, of which the following is a specification.

10 This invention relates to improvements in talking machines, and more particularly in the record-carrying elements or turntables comprised therein. The invention aims generally to overcome various defects of a recognized and serious character inherent in the present-day forms of turntables in general use, and by so doing to improve the acoustical qualities of reproduction, to add to the utilitarian value, to materially improve the 20 appearance, and to add to the effective life of the turntable in general.

According to present practice, it is universally the custom to use either the cast or pressed metal construction for talking machine turntables, and after plating this product a covering is applied over the entire upper surface consisting of felt, velour or other fabric of like character which supports the record or tablet through complete contact 30 with the under or unused side.

Depending upon the character of the various metals utilized and the formation of the flange which is usually provided at the edge of the turntable for brake application, the general structure constitutes a bell form and, like one, tends to increase the already resonant quality of the metal. Hence, it necessarily follows that extraneous mechanical noises which may be created by the driving mechanism, by the friction of the reproducing needle traveling in the record groove, or by the reproduction of the music itself, will be readily transmitted into the turntable. The latter, in turn, will 40 turn these vibrations through the covering and into the record, blurring and otherwise impairing the quality of the reproduction, so that perfect reproduction is greatly impaired, if not practically impossible, with 45 the present form of turntable and with the present principle of supporting records through complete contact between the under surface of the record and the upper surface of the turntable.

50 It will be agreed that the most perfect

acoustical insulator from the resonance of the physical form of the turntable is air, and that if the record could be supported and played without contact with any solid medium, the best reproduction would be secured. Such a condition, however, is, of course, impossible; but on the other hand, it will be apparent that the nearest approach thereto would be a material aid to the acoustical qualities of reproduction. In this respect, my invention creates a heretofore undeveloped form of turntable, according to which I eliminate all of the disadvantages mentioned above by supporting the record in a new and unique manner, *i. e.*, by means of a narrow ridge or bead, preferably in the form of a closed geometrical figure, which projects above the uncovered surface of the turntable so as to support the record with the least amount of solid contact and to allow the least amount of transmission of extraneous noises from the record-supporting medium into the record and thence into the reproducing devices. In other words, the improved supporting means, which comprises the most important feature of my invention, provides the greatest possible amount of vibratory or acoustical insulation between the record and the turntable by supporting the record with the least amount of solid contact with the turntable surface.

This arrangement possesses the further advantage that it enables the removal of a record from the turntable easily and without injury either to the finger nail or to the fabric covering, and to that extent constitutes an additional feature of my invention. This may be explained by the fact that the provision of the ridge results in dividing the surface area of the turntable into different definite zones, the position and shape of which are dependent upon the location and form of the ridge. In any event, however, at least one of these zones has a smooth, hard uncovered surface, due to the omission of the fabric therefrom, which zone underlies the edge of the record supported upon the shoulder and, in consequence, provides a space permitting not only the easy insertion of the finger beneath the under surface of the record but also permitting the application of pressure in a downward direction upon the free edge of the record in such a manner that the ridge will constitute a fulcrum about which the record can tilt. The

length of the longer or free arm of the lever thus formed by the record is so much greater than that of the shorter arm whereon the pressure is imposed that the former 5 arm will swing upwardly an appreciable distance away from the turntable and, hence, can readily be grasped by the operator, the central portion of the record disengaging the projecting end of the spindle.

10 At the same time that the record is tilted or rocked in this way, it can be slid inwardly of the turntable across the ridge, to facilitate its grasp, due to the fact that whereas its under face will readily slide across the 15 top of the shoulder, the edge of the record will slide with equal ease over the smooth surface of the turntable, so that the removal of the fabric positively contributes to a considerable extent to the success of the operation just described.

15 By employing the improved ridged construction, with the resultant supporting of the record slightly above the surface of the turntable, a further advantage is obtained 20 in that there is a complete avoidance of the danger of the under face of the record becoming scratched during its positioning and subsequent removal. At the present time, it is usual, excepting in the most expensive 25 records, to utilize both faces of the disk for recording purposes; but since the fabric covering ordinarily employed acts as a collector of dust and other foreign substances which may be deposited thereon from the 30 atmosphere, it will be apparent that should any fine particles of grit or other hard material be contained in such deposit, they will be liable to rub or scratch against and probably injure the sound grooves on the 35 under side of the record during the changing operation, thereby spoiling the record for subsequent reproduction to a greater or less degree according to the extent of the injury. On the other hand, the supporting 40 of the record in elevated position will entirely eliminate this potential source of injury, as the record will be maintained out of contact with the surface of the turntable and rest upon the top of the ridges or ribs, 45 so that this is likewise an important feature 50 of the invention.

In the same connection, it will be observed that the omission of the covering and the consequent avoidance of the collection 55 of dust thereon serves a still further purpose in that the discoloration of the covering produced by the deposits of foreign material and by its exposure to sunlight and, possibly, to dampness or moisture is entirely done away with; whereas, on the 60 other hand, the uncovered metal or other hard surface which is thus left exposed lends itself perfectly to polishing, plating, 65 enameling and other types of ornamentation and, hence, may be caused to present a

most attractive and artistic appearance, besides having the property of being readily cleaned whenever desired.

So also there is the further advantage to be derived that in the case of warped records, a more satisfactory frictional engagement is provided than is the case with a table having a completely covered surface occupying a single plane, because of the fact that the arc of the warped section 70 merely bows into the space provided above the plane of the table surface and on the inside of the ridge when the record is placed upon the table convex side down, while the space on the outside of the ridge 75 is utilized in this connection with a record placed concave side down.

In addition to the foregoing features, the invention also resides in the provision of a construction according to which the turntable may occupy a position approximately 80 flush with the deck of the cabinet or machine, while still providing a means whereby an adequate finger-space is obtained for lifting off records, even of large stock sizes. 85 This arrangement has the advantage that the operative height of the tone arm may be reduced, with a resultant decrease in the waste of valuable room space in the perpendicular measurement of a machine. In the 90 case of large-size records, the object indicated is accomplished by forming a groove or depression of semi-circular or equivalent section which is constructed partly in the edge of the turntable and partly in the deck, 95 and which underlies the edge of the record, thus enabling the fingers to be readily inserted beneath said record edge and the record then lifted off the table. 100

Other and further objects and advantages 105 will appear in the course of the following description; but it is to be understood that no limitation to the precise structure herein disclosed is contemplated or intended, but that modifications and changes may readily 110 be made within the scope of the invention as subsequently claimed. Parts of the invention may also be used to the exclusion of others, and in other and different environments. 115

In the accompanying drawing,

Figure 1 is a plan view of a turntable constructed in accordance with the invention, showing also the deck or motor board whereon it is mounted;

Fig. 2 is a diametric section on line 2-2,

Fig. 1;

Fig. 3 is an enlarged detail sectional view of one of the ribs, and

Figs. 4, 5 and 6 are diametric plan views, 125 showing various other arrangements of the ribs.

Referring more particularly to the drawing, 1 designates the turntable as a whole and 2 the deck, motor board or panel. The 130

turntable is carried by the vertical spindle 3 and may be mounted thereon in the usual way or, if desired, in the manner illustrated in Fig. 2, in which instance the tip of the spindle, instead of passing completely through the turntable, will fit in an upwardly extending socket 4 formed in the surface of the turntable, the latter being provided, in turn, with an integral, upstanding lug or projection 5 which is located directly above the socket and hence, in line with the spindle so that it will act as the centering means for the record. The deck may likewise be of the ordinary construction 15, and in that case the turntable will, as usual, occupy a slightly elevated position with relation thereto; or, instead, the central portion of the deck may be cut away to form a circular opening 6 of approximately 20 the same diameter as the turntable, which latter will then be arranged in such opening with its upper surface substantially flush with that of the deck, as represented in Fig. 2.

25 As has already been stated, it is the purpose of this invention to omit the usual covering of felt, velour or other fabric, either partly or wholly, and to rest the record, which is indicated more or less diagrammatically at 15, upon an improved form of support in such a manner that its grooved under face will be spaced a slight distance above the upper surface of the turntable. Such support preferably consists of one or more narrow or thin ridges which, in turn, are composed of narrow or thin upstanding ribs. These ridges may be arranged at any desired point or points on the turntable, and they may be concentric 30 with each other and with the turntable or may be located eccentrically with relation thereto. They may be continuous, or non-continuous; that is to say, each of them may consist of a single, continuous or integral 35 rib or projection, or may consist of several structurally-separate ribs or projections disposed end to end with their confronting ends either in contact with or spaced from one another, and in the latter instance the 40 individual ribs or sections may be either straight or curved. They may, if desired, be disposed radially, and they may be constructed of the same material as, and as an integral part of the turntable, or they may 45 be of different material and either metallic or non-metallic, as desired; all of such arrangements, as well as others not specifically mentioned, falling within the scope of the invention.

50 For present purposes, however, the arrangement disclosed in Fig. 1 may be regarded as preferred, according to which there are two of the above-mentioned ridges indicated at 7 and 8, disposed in spaced, 55 concentric relation to each other and to

the peripheral edge and the axis of the turntable. Each of the ridges forms a closed, geometrical figure, in this instance a circle, and consists of a single, continuous rib which is itself formed of wood or similar 70 fibrous material and is suitably anchored or secured in a correspondingly shaped seat 9 provided in the upper surface of the turntable.

Where the rib is constructed of non-metallic material, such as that just mentioned, it may be advisable to provide it with a friction covering 10, (Fig. 3), which may be wrapped spirally around the rib, as shown, or may extend only over its rounded 80 or convexed upper edge. Such covering may consist of a continuous strip of felt, velour or other cloth; or it may consist of lead tape or the like.

In the modified arrangement indicated 85 diagrammatically in Fig. 4 there is a single ridge 7', which likewise has the form of a circle; but which, instead of being constructed of a single, continuous rib, is made up of a plurality of separate arcuate ribs 90 7", the adjacent ends of which are slightly spaced from each other. In Fig. 5, there is also a single ridge 7" in the form of a closed, geometrical figure; but such figure in this instance, has the shape of a regular 95 polygon, the component members or ribs of which are indicated at 7". In Fig. 6, the ridge 7" is star-shaped, and is made up of radial ribs 7", and still other shapes and figures may be adopted.

In all of the above constructions, it will be observed that the ridge—and it is to be noted that such term is employed to designate the record-supporting means as a whole and as distinguished from its component 105 ribs or members—has the effect, irrespective of its shape, of dividing the upper surface area of the turntable into different definite zones, at least one of which (but preferably all of which) has a smooth, uncovered surface which, in the case of the ordinary metal table, will usually be polished. Thus, in the Fig. 1 construction, the ridges will define outer and inner annular zones 11 and 12 and a circular inner zone 13; while in Figs. 4 110 and 5, the outer zones 11' and 11" will be substantially annular, and the inner zones 12' and 12" will in one case be circular and in the other case polygonal. In Fig. 6, the radiating ribs 7" will define a set of sector-shaped zones 11", which may or may not be exact counterparts according to the arrangement of the ribs. These uncovered spaces or zones may be ornamented in a great number of different ways to meet the requirements of the interior decorator or cabinet maker in carrying out the color scheme or decorative idea adapted in the cabinet of the machine, or for other purposes of a like 120 nature.

The substantially annular outer ridge serves the added function of constituting a fulcrum about which the record may be tilted when pressure in a downward direction is imposed upon its outer marginal edge, at any point thereof, the distance between such point and said rib being so small as compared with that between the rib and the diametrically opposite point, that the latter 10 point will be moved in an upward direction sufficiently far to cause the record to clear the top of the spindle or the centering projection 5, according as one construction or the other is adopted. Furthermore, by 15 reason of the smooth hard surface which is provided immediately outside the ridge or rib, the edge of the record is enabled to slide easily over the table toward the spindle without the least friction whatever, 20 thereby facilitating the grasping of its opposite portion by the other hand of the operator; whereas the depressed or table-engaging edge might tend to catch in the felt or velour covering if provided. This operation 25 will be readily understood from Fig. 2, in which the tilted position of the record is indicated in dotted lines.

The removal of the records is also facilitated by the provision of an annular finger-space which exactly underlies the edge of 30 the record. In the case of records of small stock sizes (ten inches and less), such space will be produced consequent upon the supporting of the record in elevated position 35 above the surface of the turntable upon the inner rib or ridge; it being understood, of course, that the diameter of such records will exceed that of the zone or space inclosed by the ridge, so that the overhang of the 40 record edge beyond the rib will produce a space or recess into which the fingers can be inserted. The same will also hold true for the large 12-inch records, in which case the finger space will be formed beyond the outer 45 ridge or rib and between the latter and the edge of the turntable.

In case it is desired to locate the turntable in a plane substantially flush with the deck, as illustrated in Fig. 2, then a lifting groove, 50 recess or depression for the large-size records, which is indicated at 14, will be formed partly in the edge of the turntable and partly in the edge of the deck opening 6, the two halves 14' and 14² of such groove 55 being substantial counterparts and of any desired depth, width and cross-sectional shape commensurate with the thickness of the deck and turntable.

The several features described above are 60 independent of the material of which the turntable is constructed, provided, of course, that the turntable, whether formed of metal, wood, glass, composition or other substance or material, has a hard, smooth upper sur-

face; and in any or all of such instances, the 65 aforesaid surface may or may not be polished to increase its smoothness, and may not be plated or otherwise ornamented in various ways.

What I claim is:

1. A talking machine turntable, provided upon its upper surface with a plurality of narrow, upstanding ribs to support a record above said surface.

2. A talking machine turntable, provided 75 upon its upper surface with a plurality of narrow, upstanding ribs to support a record above said surface, said ribs conjointly forming a circle.

3. A talking machine turntable, provided 80 upon its upper surface with a narrow, annular, upwardly-projecting ridge to support a record above said surface.

4. A talking machine turntable provided 85 upon its upper surface with a narrow, upstanding record-supporting ridge which has the form of a substantially-closed, geometrical figure dividing the surface area of the turntable with respect to said ridge into outer and inner zones, the former having a 90 smooth surface.

5. A talking machine turntable, provided 95 upon its upper surface with a narrow upstanding ridge to support a record above said surface, said ridge having a friction surface to engage the under side of the record.

6. A talking machine turntable, provided 100 upon its upper surface with a narrow upstanding ridge to support a record above said surface, said ridge having a friction covering applied to it to engage the under side of the record.

7. In a talking machine, the combination 105 of a motor deck having an opening therethrough; a spindle passing through said opening; and a turntable mounted on said spindle substantially flush with the surface of the deck, said deck and turntable being constructed to conjointly provide an annular finger-space which underlies the edge 110 of a record on the turntable and which is formed partly by the edge of the turntable and partly in the deck.

8. In a talking machine, the combination, 115 with the motor deck, of a turntable mounted substantially flush with the surface of said deck and provided at its peripheral edge with a continuous finger-space which is overhung by the edge of a record on the turntable, said deck having an arcuate depression in its surface which is concentric with said finger-space and which registers with the same so as to form a lateral extension thereof.

In testimony whereof I have affixed my signature.

JOHN A. DAVIS.
